UNITED STATES PATENT OFFICE.

JOSEPH H. ASSELIN, OF WATERBURY, CONNECTICUT.

COMBINATION STOOL AND STEPLADDER.

Application filed March 22, 1927. Serial No. 177,249.

This invention relates to furniture, and more particularly to a combination stool and stepladder in which the single ladder step is adapted to be folded under the stool member 5 when not in use.

One object of this invention is to provide a combination stool and stepladder having spring latches for detachably holding the ladder step in its inactive folded position.

10 A further object is to provide a device of this nature which will be simple in construction, inexpensive to manufacture, easy to install and manipulate, compact, ornamental in appearance, and very efficient and durable 15 in use.

With these and other objects in view there has been illustrated on the accompanying drawings one form in which the invention may be conveniently embodied in practice.

20 Fig. 1 represents a side view of the combination stool and stepladder.

Fig. 2 is a transverse sectional view of the same with the ladder step shown in collapsed position.

25 Fig. 3 is a front view of the same.

Referring now to the drawings in which like reference numerals denote corresponding parts throughout the several views, the numeral 10 indicates a horizontal rectangular stool member secured in any suitable 30 manner upon the top of a pair of side supporting members 11 and 12. Each of the members 11 and 12 increases in width from top to bottom and has a centrally located 35 open V-shaped recess 13 of ornamental shape extending up from its bottom edge and forming legs 14 and 15 on either side thereof.

The upper forward portions of the side supporting members 11 and 12 are provided 40 with elongated slots 16 having rounded bottom ends 16^a. The slots 16 are parallel with the inclined front edges of the supporting members 11 and 12 and extend about one-half way down the length of said side members forming guideways for the opposite 45 ends of a pivot rod 17. The rod 17 is rigidly secured in any suitable manner as by screws 18 to the under side of a ladder step 19 which has a pair of legs 20 and 21 secured thereto as by screws 22 and 23. The 50 pivot rod 17 has its ends extended in both directions at 24 and 25, and said ends are adapted to slide in the slots 16 formed in the side supporting members 11 and 12, a pair 55 of knobs 26 and 27 being provided on the extremities of said rod 17.

In order to hold the ladder step 19 in the collapsed position shown in Figs. 2 and 3, provision is made of a pair of convoluted hair-pin-shaped metal clips 28, said clips 60 being located in the top of the slots 16 and being secured as by screws 29 to the bottom surface of the horizontal top member 10.

In operation, when it is desired to fold the ladder step 19 from the position shown in Fig. 1 to the collapsed position shown in Figs. 2 and 3, it will only be necessary to raise the step vertically and then turn the step 19 with its leg 20 in a clockwise direction until the step 19 comes to a position 70 parallel to the inclined edge of the supporting members 11 and 12. The step 19 may then be pushed upwardly until the ends of the rod 17 snap into the clips 28. The step 19 will be held in its collapsed position by 75 the clips 28 indefinitely until it is desired to use the device as a stepladder again.

While there has been disclosed in this specification one form in which the invention may be embodied, it is to be understood 80 that this form is shown for the purpose of illustration only, and that the invention is not to be limited to the specific disclosure but may be modified and embodied in various other forms without departing from its 85 spirit. In short, the invention includes all the modifications and embodiments coming within the scope of the following claims.

Having thus fully described the invention, what is claimed as new, and for which it is 90 desired to secure Letters Patent, is:

1. In a collapsible combination stool and stepladder, a stool member, a step member adapted to be folded within said stool member and having a rod journaled in said stool member, said stool member having a resilient clip for detachably engaging said rod to hold said step member in collapsed position. 95

2. In a collapsible combination stool and stepladder, a step member, a stool member having a slot, means mounted on said step member and slidable in said slot, a clip on said stool member in the end of said slot for detachably holding said means, whereby said step member may be folded up out of 100 the way into collapsed position when not in use. 105

In testimony whereof, I have affixed my signature to this specification.

JOSEPH H. ASSELIN.
